UNITED STATES PATENT OFFICE.

FREDERIC BILLON, OF SOLOTHURN, SWITZERLAND.

ELECTRICAL IGNITION APPARATUS FOR INTERNAL-COMBUSTION ENGINES.

1,386,231.

Specification of Letters Patent.

Patented Aug. 2, 1921.

Application filed February 13, 1918. Serial No. 216,905.

To all whom it may concern:

Be it known that I, FREDERIC BILLON, a citizen of the Swiss Republic, residing at Solothurn, Switzerland, have invented certain new and useful Improvements in Electrical Ignition Apparatus for Internal-Combustion Engines, of which the following is a specification.

This invention has for its object to provide an improved electrical ignition apparatus for producing any desired time-succession of the ignition, wherein the rotor is balanced statically, dynamically and magnetically.

15 In ignition apparatus of the kind specified in Patent No. 1,361,133 granted December 7th, 1920, the weight of the rotor is perfectly balanced from a dynamic point of view. In some constructions according to 20 the said patent, the static balance however can be produced only by the use of special counterweights.

The present invention allows of producing a balance of the weight both statically 25 and dynamically without the use of special counterweights in connection with the rotor of the ignition apparatus. This is effected according to the present invention by a peculiar formation of the parts that constitute 30 the magnetic circuit of the apparatus. This improved formation consists in arranging the pole pieces of a pole both as regards the fixed portion as well as the rotary portion, in two groups in the axial direction side by 35 side with a gap between, while the corresponding pole pieces of the other pole are not so sub-divided and are arranged opposite to this gap.

This improved arrangement allows the 40 masses of both the rotor and the stator to be distributed symmetrically in a complete manner to a central plane in the direction of the axis, and at the same time also symmetrical to a plane at right angles to the 45 axis, so that the masses are balanced dynamically as well as statically.

This same arrangement allows of having 50 always on both sides equal overlapping of the pole pieces, so that the magnetic forces are equally balanced.

Two constructional examples of this invention are illustrated in the drawings.

Figure 1 illustrates perspective views of the two sides of the stator, with projecting 55 double poles on one side thereof and a single

pole on the opposite side, all provided with concave faces.

Fig. 2 is a similar view of the corresponding rotor with bifurcated pole pieces, consisting of a permanent magnet. 60

Fig. 3 illustrates a cross section through the yokes and the rotor in their assembled condition.

Figs. 4 and 5 illustrate diagrammatically the mutually opposite pole surfaces of the 65 yoke and the rotor in different relative positions, in developed views, showing the positions of the rotor in which the flux passes through the zero point.

Figs. 6 to 10 illustrate a modified constructional form, in which— 70

Fig. 6 shows in perspective views of the two sides of the yoke;

Fig. 7 shows a cross section through the parts of the yoke and the rotor in their 75 assembled condition, and

Fig. 8 the corresponding rotor;

Figs. 9 and 10 are diagrammatic views of 80 opposite pole surfaces of the yoke and the rotor in different relative positions, in developed views, showing the positions of the rotor in which the flux passes through the zero point.

In both constructions the stationary portion of the magnetic circuit is constituted by 85 a yoke that carries the induction winding, while the rotary portion consists of a permanent magnet.

Referring to Figs. 1 to 5,

Fig. 1 shows the two side members of the 90 yoke formed with projecting poles. One side member of the yoke is split in such a manner that the two portions A and B there-of have a gap between them. Opposite this gap is arranged the pole piece C of the other 95 side member of the yoke.

Fig. 2 shows the rotor in which the yoke members formed by suitable recesses in the cylindrical periphery of the magnet, are arranged in an analogous manner. In this rotor the pole pieces N are subdivided into two groups. Opposite the gap situated between the two groups there are arranged the pole pieces S of the other pole. 100

The positions of the pole pieces A and B 105 of the fixed portion or stator relatively to the positions N and S of the rotor, are illustrated respectively in Figs. 4 and 5 which are developed views showing those positions of the rotor in which the flux passes through 110

the zero point, and the igniting spark is produced.

The position shown in Fig. 4 corresponds to the position of the rotor shown in Fig. 3

5 in which the N-pole is leaving the stationary portions A and B, and the S-pole is leaving the stationary portion C on the yoke.

Fig. 5 shows the position which is reached after about half a revolution, in which the 10 S-pole is leaving the portions A and B, and the N-pole is leaving the portion C on the stator.

A comparison of the position, for example, of the N-pole in Fig. 4, with the position 15 shown in Fig. 5, shows that in one revolution two ignitions are produced at angular distances apart of $180^\circ - \frac{\alpha}{2}$ and $180^\circ + \frac{\alpha}{2}$.

By suitable formation and dimensions of 20 the projections or recesses of the pole pieces, the angle $\frac{\alpha}{2}$ and consequently the time-interval between two successive ignitions may be chosen to suit the angle α of the cylinders of 25 the internal combustion engine.

In the constructional form of the im-

proved ignition apparatus illustrated in Figs. 6 to 10, the rotor has projecting pole pieces, while the pole pieces of the stator are formed by recesses.

30 Figs. 6 to 10 correspond respectively with Figs. 1 to 5, and the equivalent parts are marked with the same reference letters as in the last mentioned figures.

What I claim is:—

35 In an electrical ignition apparatus for an internal combustion engine, for producing any desired time-succession of the ignitions, the combination of a stator of which one pole piece is subdivided so as to form two 40 groups of pole tips, said groups being located axially side by side, but separated by a gap, and a rotor of which one pole piece is subdivided so as to form two groups of pole tips, said groups being located axially side 45 by side, but separated by a gap, while the pole pieces of the other pole of both said stator and said rotor are located respectively opposite said gaps.

50 In testimony whereof I have signed my name to this specification.

FREDERIC BILLON.
